UNITED STATES PATENT OFFICE.

MANUEL BRETOS Y CLAVERIA, OF SANTIAGO DE CUBA, CUBA.

AWNNG.

Application filed April 5, 1924, Serial No. 704,435, and in Cuba February 28, 1924.

This invention refers to awnings, and its principal object is to provide a form of awning which permits extending or folding of the same in an efficient and quick manner, without the difficulties inherent in former constructions.

An object of my invention is to provide means to roll up the hoisting cable of the awning which permit the extension or the folding of the awning, said means comprising a winding drum operated by means of a leaf spring and a mechanism to give the necessary tension to the spring.

Other advantages and considerations pertaining to this invention will be seen in the course of the specification considered with the aid of the annexed drawings, in which similar characters of reference designate similar parts and wherein:

20 Figure 1 is a side elevation of an awning provided with the improvements which constitute the present invention.

Figure 2 is a front elevation of the same.

25 Figure 3 is a side elevation in detail of the awning winding drum and its standard.

Figure 4 is a plan view of same.

Figure 5 is a vertical transverse section on line 5—5 of Figure 3.

30 Figure 6 is a longitudinal vertical section on line 6—6 of Figure 4.

Figure 7 is a sectional view showing means of engagement and fastening of the drum standard, parts being in elevation, and

35 Figure 8 is a perspective view in detail of the casing to house the standard of the drum.

A metallic folding door 1 having hinged folding plates 1', and lateral guides 2 in engagement with frame 3, forms an awning, slideable in the frame 3, and foldable or extensible by means of folding mechanism which is described in the following.

40 At one side of the door, in the wall for example, is a cavity 4, in which is housed a casing 5, detailed in Figure 8, and which

45 has its front part open and of rectangular section, and its back part rounded and adapted to the shape of the cavity 4. The

50 front part of the casing 5 projects out from the cavity and has on its upper side an opening wherein are loosely mounted two parallel

55 friction rollers 6, and presents, on the upper and lower sides, ears 5''. The casing 5, near

its front lateral edges, also has pins 5''' and 5''', the object of which will be explained further on, and the casing is fixed in the cavity 4 by angles 4'.

The casing 5 receives the standard of the winding drum, as detailed in Figs. 3 to 6 inclusive, including plates 7 joined at the front to a vertical plate 9 which serves as a cover for the casing 5 when the standard is placed therein and secured by screws passing through registering bores 9'', 9''' and the ears 5'' of the casing 5 and corresponding bores 9' in the plate 9.

65 The plates 7 are rounded on their rear ends and have an engagement notch 8, the function of which will be later explained, and between these plates is fixed a horizontal shaft 10 held on the outer side by keys 10', and mounted loosely on this shaft and projecting upwardly from the plates 7, is a drum 11, the sides of which are spaced and joined together by pins 13, and from the sides, projecting radially outward, are pins 75 11'.

70 Around the drum 11 is loosely mounted a reel 14, spirally channeled to receive a hoisting cable 17 which is fixed at one end at points 14' which project from one of the 75 channels of the reel.

75 Inside the drum 11 is placed a spiral spring 12 of a strength previously calculated for its work, one end of the spring being fixed to the shaft 10 and its other end to one of the spacing pins 13.

80 On one side of the drum is a notch 11' arranged to register with a notch 14'' in one of the edges of the reel so as to receive a pawl 15 pivoted on 15' to one of the sides 90 of drum 11.

85 At 16' is pivoted a stop arm 16 provided with a stop ear 16'', and to the plate 9 is fastened, by angular braces 13'', an arm 13'.

90 The purpose of the arm 16 is to engage one of the pins 11'' in varying the tension of the spring 12 as will appear hereinafter.

95 The drum standard is placed in the casing 5 the upper edges of its sides being positioned under the pins 5''' and the plate 9, 100 constituting the cover of the opening of the casing, as has been explained above, is secured by screws passing through the bores 9' therein and bores 9'' and 9'''.

The hoisting cable 17, wound on the reel 14, is passed up between the rollers 6, over guide pulleys 18' and 19', mounted in pulley casings 18 and 19 on the ends of a collapsible shaft 20 supported by brackets 21, and the pulley casings also have an oscillating movement due to a slot and stop engagement 20'.

Attention is called to the fact that the shaft 20, being hollow, the cable 17 can be guided through it from the pulley 18' to the pulley 19' and then downwardly, under a pulley 22 in a pulley casing 22' at the upper part of the door, then in and over a pulley 23 in the pulley casing 23' held under the top of the door, around a guide pulley 24 which is mounted in the end of a bracket 25 fastened to the lower part of the awning and then over a pulley 23' in the pulley casing 23, under a pulley 22' in the pulley casing 22', to be fastened at the lower end of the pulley casing 19.

Besides the arrangement explained, a shock absorber is provided for the awning, consisting of a bracket 27, and a rod 28 around which is coiled a spring 29, and which operates a stop 26 inside of which is lodged the spring 29.

To operate the folding or the extending of the awning it is only necessary to pull downward or push upward on the cable 17 to effect the folding of the awning as is shown in dotted lines in Fig. 1, or the extending of the same as is shown in full line in the same figure, it being understood that the reel 14, fixed relatively to the drum 11, due to the engagement of the pawl 15, together with the hoisting cable 17, will be wound in one direction or the other due to the tension of spring 12, when it is moved.

The shock of operation of the awning will be taken up by the flexible stop 26.

When it is desired to vary the tension of the spring 12, the screws which hold the plate 9 to the casing 5 will be removed, and the standard of the drum will be pulled outwardly, the notches 8 being held in engagement with the pins 5''' of the casing 5 and the arm 13', the free end of which presents a recess for supporting the same, will rest on pin 5''', and the bracket 7 will hang outwardly as shown in Figure 7 to permit handling as desired.

Being in the position shown, if it be desired to vary the tension of the spring, the pawl 15 is disengaged from its adjustment notches, and the reel 14 will remain loosely mounted around the drum 11, and will be turned (see Figure 3) until one of the pins 11'' engages stop arm 16, so that upon moving the drum 11 forward, with a suitable tool, which will be engaged by pins 11'' the tension of the spring 12 can be varied by the rotation of the drum 11, in the proper direction. This being done, the reel 14 is turned so that the notch 14'' of the same will regis-

ter with the notch 11' of the drum, when the pawl 15 will become engaged, the reel 14 therein being again held fixed to the drum 11, and the drum standard can again be housed in casing 5.

Having described my invention and one manner in which same can be performed, what I wish to protect is the following:

1. An operating means for awnings and the like, comprising, a standard, a shaft 70 fixed in the standard, a drum rotatably mounted on the shaft, a reel rotatably carried by the drum, matching notches on the drum and reel, a detent receivable in the notches to fix the reel to the drum, and a spiral spring housed in the drum, one end of the spring being fixed to the shaft and the other end to the drum.

2. An operating means for awnings and the like, comprising, a standard, a shaft 85 fixed in the standard, a drum rotatably mounted on the shaft, a reel rotatably carried by the drum, matching notches on the drum and reel, a detent receivable in the notches to fix the reel to the drum, a spiral 90 spring housed in the drum, one end of the spring being fixed to the shaft and the other end to the drum, pins projecting from one side of the drum for rotating the drum, and a stop arm pivoted to the standard and cooperating with the pins.

3. An operating means for awnings and the like, comprising, a standard, a shaft fixed in the standard, a drum rotatably mounted on the shaft, a reel rotatably carried by the drum, matching notches on the drum and reel, a detent receivable in the notches to fix the reel to the drum, a spiral spring housed in the drum, one end of the spring being fixed to the shaft and the other end to the drum, the standard including a front plate and spaced projecting arms between which arms the drum is mounted, the upper edges of the arms being notched, a holding arm pivoted to the front plate, an open ended casing to receive the standard and parts carried thereby, and pins on the casing projecting inwardly thereof to engagingly cooperate with the notched arms and holding arm when the standard and its parts 105 are partly withdrawn from the casing.

4. An operating means for awnings and the like, comprising, a standard, a shaft fixed in the standard, a drum rotatably mounted on the shaft, a reel rotatably carried by the drum, matching notches on the drum and reel, a detent receivable in the notches to fix the reel to the drum, a spiral spring housed in the drum, one end of the spring being fixed to the shaft and the other end to the drum, pins projecting from one side of the drum for rotating the drum, a stop arm pivoted to the standard and cooperating with the pins, the standard including a front plate and spaced projecting arms between 115 120 125 130

- which arms the drum is mounted, the upper edges of the arms being notched, a holding arm pivoted to the front plate, an open ended casing to receive the standard and parts carried thereby, and pins on the casing projecting inwardly thereof to engagingly cooperate with the notched arms and holding arm when the standard and its parts are partly withdrawn from the casing.
5. An operating means for awnings and the like, comprising, a standard, a shaft fixed in the standard, a drum rotatably mounted on the shaft, a reel rotatably carried by the drum, matching notches on the drum and reel, a detent receivable in the notches to fix the reel to the drum, a spiral spring housed in the drum, one end of the spring being fixed to the shaft and the other end to the drum, the standard including a front 10 plate and spaced projecting arms between which arms the drum is mounted, the upper edges of the arms being notched, a holding arm pivoted to the front plate, an open ended casing to receive the standard and parts carried thereby, pins on the casing projecting inwardly thereof to cooperate with the notched arms and holding arm, two of the pins being positioned at the level of the top edge of the arms when the standard is inserted into the casing, and a third of the pins being positioned above the level of said two pins, the notched arms, and the holding arm receiving the said three pins to hold the standard and its parts in a position partly withdrawn from the casing for 15 facilitating adjustment of the spiral spring tension.
6. An operating means for awnings and the like, comprising, a standard, a shaft fixed in the standard, a drum rotatably mounted 40 on the shaft, a reel rotatably carried by the drum, matching notches on the drum and reel, a detent receivable in the notches to fix the reel to the drum, a spiral spring housed in the drum, one end of the spring being 45 fixed to the shaft and the other end to the drum, pins projecting from one side of the drum, a pawl pivoted to the standard and cooperating with the pins, the standard including a front plate and spaced projecting arms between which arms the drum is mounted, the upper edges of the arms being notched, a holding arm pivoted to the front plate, an open ended casing to receive the standard and parts carried thereby, pins 50 on the casing projecting inwardly thereof to cooperate with the notched arms and holding arm, two of the pins being positioned at the level of the top edge of the arms when the standard is inserted into the casing, and a third of the pins being positioned above the level of said two pins, the notched arms, and the holding arm receiving the said three pins to hold the standard and its parts in a position partly withdrawn from the casing 55 for facilitating adjustment of the spiral spring tension.
- In testimony whereof I have signed my name to this specification.
- MANUEL BRETOS y CLAVERIA.
